UNITED STATES PATENT OFFICE

THOMAS ANDERSON, OF HOUSTON, TEXAS

PIPE WRENCH

Application filed July 3, 1928. Serial No. 290,059.

This invention relates to pipe wrenches on the order of the Stillson wrench, and one object of the present invention is to provide a wrench of this character which is adjusted by 5 turning the handle of the wrench, making it unnecessary for the operator to shift his hands from their working position.

A further object is to so form the pivoted jaw of the wrench that it has a relatively 10 short radius and thus has a greater range of action than the pivoted jaws of wrenches as ordinarily made, and that it secures a firmer grip upon the part to be turned for the same reason.

15 Another object is to provide a wrench of this character which will be particularly strong and which may be as cheaply made as other wrenches of like general character.

My invention is illustrated in the accompanying drawings in which—

Fig. 1 is a side elevation of a wrench constructed in accordance with my invention;

Fig. 2 is a longitudinal sectional view thereof;

25 Fig. 3 is a top plan view thereof;

Fig. 4 is a section on the line 4—4 of Fig. 2;

Fig. 5 is a fragmentary longitudinal section through the sleeve and the thimble of the wrench shown in Fig. 1 and taken on the 30 line 5—5 of Fig. 2; and

Fig. 6 is a like view to Fig. 2 but showing a modification of the structure.

The wrench as illustrated in Fig. 1, comprises a jaw 10 having a straight shank 11 preferably rectangular in form, this shank having an extension 12 reduced in cross sectional area. This shank is provided with interrupted screw threads 13 upon its opposite edges. Fitting over and having sliding 35 engagement with the shank 11 is a sleeve or jacket 14 which has an internal diameter adapted to accommodate the portion 11 of the shank and slide freely thereon. That portion of this sleeve which is adjacent the jaw 40 10 is rectangular in cross section but the opposite end of the sleeve is circular in cross section as at 15. Disposed within the circular portion of the sleeve and engaged therewith in any suitable manner is a thimble 16

50 having an annular flange 17 at its inner end,

this thimble being adapted to slide over the reduced portion 12 of the shank 11 without interrupting the teeth or screw threads 13. Surrounding the shank portion 12 and spaced therefrom is a tubular or hollow handle 18 closed at its outer end by means of a screw cap 19 and at its inner end being formed with an inwardly extending annular flange 20 which extends over the outwardly projecting flange 17. Disposed within this hollow handle 18 and engaged therewith in any suitable manner, as for instance by the rivets, screws, pins or like members 21, is a nut 22, which is interiorly screw-threaded for engagement with the interrupted screw-threads 13. This nut is insertable into place through the opening normally closed by the screw cap 19.

It will thus be seen that by rotating the handle in one direction or the other the 70 shank and the handle with the sleeve 14 will be longitudinally shifted relative to each other in opposite directions.

The sleeve 14 carries upon it the laterally projecting longitudinally extended socket 75 23 within which is disposed the shank 24 of a jaw 25 confronting the jaw 10 and extending at right angles to the shank 24. The shank 24 as shown most clearly in Fig. 2 is pivoted upon the transverse bolt or stud 26 so which of course extends through the socket and the inner face of the shank from a point opposite the pivot bolt or stud 26 and is outwardly curved or cut away as at 27. The pivot bolt, it will be seen, is disposed adjacent that end of the socket 23 nearest to the jaw 25 and thus the radius of the jaw is rendered relatively short. By reducing this radius and by cutting away that portion of the shank 24 beyond pivot bolt 26, the pivoted 85 90 95 jaw is permitted to turn outward to a greater extent than is possible, as in the ordinary Stillson wrench, where the jaw is pivoted adjacent its extreme inner end.

In Fig. 6, I have illustrated a modified form of this wrench in which the handle 18^a has an inwardly extending annular flange 20^a as heretofore described, but in which the jacket or sleeve 14^a is itself formed with an annular groove 28.

Under these circumstances the flanged end of the handle would have to be forced over the flanged end of the sleeve 14^a and seated in said groove 28. I do not wish to be limited 5 to having the handle formed with an in-turned flange and the shank of the jacket or sleeve formed with an outwardly turned flange or with a groove, as obviously the sleeve might be formed with an inwardly 10 turned flange engaging with a groove formed in the handle or with an outwardly turned flange on the handle. In other words, the relative structure of the engaging ends of the handle and sleeve might be reversed.

15 It is obvious also that many minor modifications might be made in the details of this wrench without departing from the spirit of the invention as defined in the appended claims.

20 What I claim is—

1. A wrench of the character described comprising a jaw having a shank, the shank having screw threads, a sleeve slidably mounted upon the shank, a handle surrounding the shank and having a removable cap at 25 its outer end, a nut engaging the screw threads, and insertable in the handle through the opening normally closed by said cap, the handle and sleeve having swiveled engagement with each other and the sleeve having a laterally projecting socket, a jaw confronting the first named jaw and having a shank extending into said socket and pivoted therein, the pivot being disposed adjacent that end 30 of the socket remote from the handle and the inner face of the jaw shank being cut away from said pivot point to the extremity of the shank adjacent the handle to thereby permit the shank to be swung outward or inward.

40 2. A wrench of the character described comprising a jaw having a shank, the shank being reduced and provided with screw threads, a sleeve slidably mounted upon the unreduced portion of the shank, a hollow handle surrounding the reduced portion of 45 the shank and carrying a nut within it engaging the screw threads of the shank, the sleeve and handle being formed one with an outwardly projecting flange and the other with an inwardly projecting overlapping flange whereby to secure a swiveled engagement between the handle and the sleeve, the sleeve at its end remote from the handle being laterally offset and longitudinally extended to 50 form a socket rectangular in cross section and a jaw confronting the first named jaw and having a longitudinally extending shank fitting in the socket and pivoted thereto, the inner face of the shank beyond the pivot being inclined outward and rearward away from the sleeve.

55 3. A wrench of the character described, comprising a jaw having a shank formed with interrupted screw threads, a sleeve mounted upon the shank for longitudinal

movement, a hollow handle surrounding the screw-threaded portion of the shank and having an inwardly extending flange at its inner end, the outer end of the handle having a cap detachably closing this end of the handle, 70 and a thimble having a flange at its end adjacent the handle, the flange coacting with the flange on the handle to secure a swiveled engagement between these parts, the thimble being attached to the sleeve and being insertable through the open end of the handle, said sleeve having a laterally offset portion formed to provide a socket, and a jaw shank extending into said socket and pivoted thereto, the shank being cut away upon its inner 75 so face and inward of said pivot.

In testimony whereof I hereunto affix my signature.

THOMAS ANDERSON.
